CLAIM

The ornamental design for a display screen or portion thereof with icon, as shown and described.

DESCRIPTION

FIG. 1 is a front view of a display screen or portion thereof with icon in accordance with a first embodiment of our new design;

FIG. 2 is a front view of a display screen or portion thereof with icon in accordance with a second embodiment of our new design;

FIG. 3 is a front view of a display screen or portion thereof with icon in accordance with a third embodiment of our new design; and,

FIG. 4 is a front view of a display screen or portion thereof with icon in accordance with a fourth embodiment of our new design.

The outermost broken lines illustrate a display screen or a portion thereof and form no part of the claimed design. The remaining broken lines illustrate portions of the graphical user interface that form no part of the claimed design.

1 Claim, 4 Drawing Sheets
